DESIGN FOR A BOTTLE

Edwin W. Fuerst, Toledo, Ohio, assignor to National Distillers Products Corporation, New York, N. Y., a corporation of Virginia

Application December 14, 1933. Serial No. 50,068

Term of patent 14 years

To all whom it may concern:

Be it known that I, EDWIN W. FUERST, a citizen of the United States, and residing at Toledo, in the county of Lucas and State of Ohio, have invented a new, original, and ornamental Design for a Bottle, of which the following is a specification, reference being had to the accompanying drawing, forming a part thereof.

In the drawing:

Fig. 1 is a side elevational view of a bottle showing my design, which is identical on the opposite sides of the bottle.

Fig. 2 is an edge elevational view thereof, both edges being of identical design.

I claim:

The ornamental design for a bottle substantially as shown and described.

Signed at Toledo, in the county of Lucas and State of Ohio, this 8th day of December, 1933.

EDWIN W. FUERST.
